UNITED STATES PATENT OFFICE.

BRODIE J. RICHARDSON AND CLAIRE S. BARBER, OF WATERBURY, CONNECTICUT.

BAG-LOCK.

1,397,455.

Specification of Letters Patent. Patented Nov. 15, 1921.

Application filed December 18, 1920. Serial No. 431,545.

To all whom it may concern:

Be it known that we, BRODIE J. RICHARDSON and CLAIRE S. BARBER, citizens of the United States, and residents, respectively, 5 of Waterbury, in the county of New Haven and State of Connecticut, have invented certain new and useful Improvements in Bag-Locks, which improvements are fully set forth in the following specification.

10 This invention relates to improvements in devices of that class available conjunctively with a suitable duplex hasp for locking together the customary hinged frame-sections of a hand-bag or the like, such devices being 15 well designated duplex hand-bag locks.

The object of this invention is to provide a lock of the character above indicated, which shall be simple and comparatively inexpensive as regards its construction; durable, efficient and reliable in practical service; 20 which shall embody certain novel features whereby is facilitated the operation of assembling the various parts thereof; and which shall possess certain well-defined advantages over prior analogous constructions. 25

The invention consists in certain combinations, details and parts to be hereinafter more fully referred to and set forth in the claims hereto appended, and whereby the attainment 30 of the foregoing object is rendered practicable.

The invention is clearly illustrated in the accompanying drawing, wherein:

Figure 1 is a top plan view of a lock embodying our said improvements, the depressible finger-piece being shown partly in horizontal section and the top plate of the housing being partly broken away.

Fig. 2 is a rear elevation thereof, a portion 40 of the rear wall of the finger-piece being broken away.

Fig. 3 is a horizontal section of same, the section being taken as along the dotted line 3-3 of Fig. 2.

45 Fig. 4 is a central, vertical, transverse section of the device, as along the dotted line 4-4 of Fig. 2.

Fig. 5 is an end elevation of the lock, the near wall of the housing being broken away.

50 Fig. 6 is a detail sectional view showing more particularly the application of a key to our improved lock.

Fig. 7 is a top plan view of a fragment of the locking-bolt made use of.

55 Fig. 8 is a view showing in perspective and detached the bolt-follower made use of,

Fig. 9 is a view similar to Fig. 8, showing the bolt-locking tumbler which we purpose making use of.

Having reference to the accompanying drawing, wherein similar reference-numerals denote like parts throughout the several views, we provide, in carrying out our present invention, a general housing formed from metal in suitable sheet-form, and which 65 consists, by preference, of a base-plate 5, top-plate 5', front wall 5" and opposite end-walls 6, 6'.

The base-plate 5 is merged at its rear edge into an upstanding retaining-lip 6", the 70 function of which will be explained hereinafter.

7 denotes a locking-bolt, freely pierced by opposite, upstanding guide-spindles 7', 7" and movable upwardly and downwardly 75 relatively thereto, said locking-bolt affording opposite, upstanding catches 8, 8' engageable, respectively, with the opposite tenons, as 9, 9', of a hasp, as 8".

The catches 8, 8' may be conveniently 80 struck upwardly from the material of the locking-bolt 7, and in such a manner that each thereof shall have an edge-face duly curved upwardly and rearwardly, all as clearly indicated in the drawing. 85

By preference the locking-bolt 7 is merged at its opposite ends into opposite, upstanding guide-terminals 10, 10' which guide-terminals, by reason of the same operating in practice between, and co-operatively with, the 90 front wall 5" and the dependent flange of the hinged, hand-bag frame-section to which our improved lock may be applied, serviceably obviate all tendency on the part of the locking-bolt 7 to unduly rock or tilt forwardly or rearwardly, and as with respect to the guide-spindles 7', 7", the latter being conveniently struck upwardly from the material of their supporting thrust-plate 10", or otherwise formed, as found expedient in 100 practice; and said thrust-plate detachedly overlying in practice the base of the housing aforesaid, between the front wall 5" and retaining-lip 6" thereof.

The locking-bolt 7 is further provided 105 with a central aperture 10'', the purpose of which will become apparent hereinafter.

11 denotes a yoke whose medial segment is transversely crimped to form a central, downturned, angular stop 11', said stop approximating in form the letter V and flanked 110 oppositely by pin-receiving pockets 12, 12',

and the opposite end-portions of said yoke being depressed relatively to the medial segment thereof for the formation of opposite feet 11" 12", said feet being freely pierced 5 upwardly by the guide-spindles 7' 7" and normally bearing downwardly on the thrust plate 10".

13, 13' denote spiral springs interposed endwise between the locking bolt 7 and the 10 feet of the yoke 11, respectively, said springs encircling, in this instance, the guide-spindles 7', 7", respectively, and respectively exerting at all times an elastic stress, upwardly on said locking-bolt, to 15 hold the same at all times yieldingly protracted, and downwardly on the yoke aforesaid, through the medium of the feet of the latter thereunder.

We further provide a bolt-locking tumbler 20 whereby the locking-bolt aforesaid may be locked against retraction, the same comprising, by preference, a relatively thin, upright, flat body 13", adapted to lie and operate against the inner face of the wall 25 5, having a rearwardly turned flange 14 at its lower edge, which underlies the thrust-plate 10", and having opposite shoulders 14', 14", whose function will be explained later hereinafter.

30 Since the flange 14 underlies the base 10", it will be apparent that the tumbler now under consideration is held yieldingly to a sliding engagement with the base-plate 5 thereunder, through the medium of the 35 springs 13, 13' bearing downwardly thereon, as indirectly by way of the feet 11", 12" and the thrust plate 10" thereunder, the latter in turn overlying and engaging the flange 14.

40 The wall 5" is provided with an opening 15, by way of which access to the tumbler aforesaid may be had for shifting the same, laterally in one direction for locking the locking-bolt against retraction, and laterally in the opposite direction for freeing the same for retraction; and in this connection, we provide a yoke-actuating pin 15' which pierces the body 13" by way of a suitable aperture 16, is fitted at its outer end, 45 exteriorly of the wall 5, with a finger-button 16', and whose free inner end-portion normally projects into and occupies one of the pockets, say 12', flanking the stop 11', and whereby, the pin being duly urged as 55 by finger-pressure in either direction against said stop, the yoke 11 is lifted against the stress of the springs 13, 13', thus permitting said pin to snap by and beyond the stop 11' and enter and occupy the opposite 60 pocket, say 12, oppositely flanking said stop, the tumbler aforesaid, through the medium of its shoulders 14' 14" being accordingly, thrown into and out of locking engagement with the locking-bolt, and in- 65 directly so, in this instance, through the

medium of a novel bolt-follower, which bears detachably downward on said locking-bolt, and which will now be described.

As here shown the bolt-follower above alluded to comprises a medial top-member 17, 70 which is merged at its rear edge into a downturned rear wall-section 17', and which rear wall-section is, in turn, merged at its lower edge into a horizontal inturned flap 17", lying beneath and in parallelism with 75 the top-member 17.

It will be noted that the member 17 is provided with an irregular key-opening 18, while the flap 17" is provided, at a point in vertical registry with the opening 18, with 80 a circular aperture 18', the latter serving for the reception of the end-lug or tip of a suitable key 18".

To facilitate the detached mounting of said bolt-follower medially on and relatively to the locking-bolt of our improved lock, and as is contemplated, the downturned end-members of said follower are merged at their lower extremities into opposite, depressed feet 19, 19' freely pierced 90 by the guide-spindles 7', 7", respectively, thus rendering the follower movable relatively thereto in unison with the locking-bolt thereunder; and when these parts are thus assembled the aperture 18' stands in 95 registry with the bolt-aperture 10", the latter being in practice, occupied to a greater or less extent by the tip of the key 18" in common with the aperture 18' thereabove, as indicated in Fig. 6.

By reason of the fact that the apertures 18' 10" stand in registry, each with the other, our improved lock becomes non-pickable; since, under these conditions, the locking-bolt may not be retracted by means, say, 105 of a false key, strip of metal, or the like inserted endwise into and more or less downwardly through the aperture 18'.

Protraction of the locking-bolt under the stress of the springs 13, 13', is limited by the 110 engagement, under normal conditions of the parts, of the top member of the bolt-follower with the top-plate of the housing thereabove.

19" denotes a hollow finger-piece which 115 rises fixedly from the bolt-follower aforesaid and projects upwardly through and beyond the top-plate of the housing as in common practice, and to permit which, the top-plate of the housing is duly cut away, 120 as at 20.

We contemplate fastening the finger-piece aforesaid to said follower by means of rivets 20' 20", and to facilitate which the finger-piece is provided with opposite, 125 depending tabs 21, 21'.

The finger-piece 19" is provided with a major opening 21" at its crown, and upwardly into said opening projects for rotative action the reduced boss or neck 22 of a 130

key-way finder 22', the latter being held with suitable freedom of action against downward displacement from its position of service by means of a retaining sleeve 22'', inserted upwardly into and snugly at the opposite side-walls of, the finger-piece 19''; and for more permanently securing said sleeve in place, the wall thereof conjointly with the side-wall of the finger-piece in contact therewith, may be suitably indented, as by means of a prick-punch, and as indicated at 23, Fig. 4 of the drawing.

It is obvious that the finger-piece together with the retaining sleeve therein should be cut away, as at 23', to provide proper clearance for the tumbler-body 13'' under depressive action of the finger-piece and to permit such action on the part of the finger-piece.

20 In practice the key-way finder is manipulated, say, by inserting the tip of a suitable key, as 18'', into the key-slot 24 of said finder, and then duly turning the key to bring said key-slot into registry with the 25 clearance-notch 24', which constitutes in effect a contracted, radial extension of the major opening 21'', whereupon is formed a key-way extending in part downwardly through the key-way finder and in part 30 through the crown of the finger-piece, and by way of which the key 18'' may be inserted downwardly through the interior of the sleeve 22'', to and downwardly through the irregular key-aperture 18, and from 35 thence downwardly to and into rotative engagement with the flap 17'', on the top-surface of which bears and rides the shoulder 24'' of the key aforesigned, the tip thereof now occupying the aperture 18, and more or 40 less the aperture 10'', whereby the key is serviceably steadied in its turning action.

Upon the key being now given a partial turn, as on its own longitudinal axis, and in the proper direction, its depressed lateral lug 25 will engage and take with it the bolt-locking tumbler aforesigned, thereby shifting such tumbler laterally and to such an extent as to bring the shoulders 14', 14'' thereof under the forward margins, respectively, of the feet of the bolt-follower aforesigned, or laterally in the opposite direction to bring such shoulders out from beneath such feet-margins, to lock said bolt-follower against depression, and hence the locking-bolt against retraction in opposition to the stress of the springs 13, 18'', or to free said follower for depression in unison with said locking-bolt, as under finger-pressure applied downwardly to the finger-piece 19'', thereby causing the catches 8, 8' to engage or disengage the tenons 9, 9', of the hasp 8'', whereby the hinged-frame sections of a hand-bag, or the like, to one of which our improved lock may be attached as in common practice, the hasp being applied to the

opposite frame-section, may be locked together or unlocked, each from the other, all according to the direction in which the key 18'' shall be turned; and under such shifting of the tumbler, the pin 15' automatically 70 snaps by the stop 11', from one pocket flanking such stop at one side thereof, to and into the pocket flanking the stop at the opposite side thereof, as hereinbefore explained.

To render the turning of the key made 75 use of more involved, the wall of the sleeve 22'' may be indented for the formation interiorly thereof of a suitable lug 26 which shall serve to bar the effective turning of said key, save in instances where the latter 80 is provided with a suitable clearance-notch 26' for coöperation with such lug; and to render the turning of the key still further involved, it will be understood that a plurality of such lugs, uniformly or variably 85 spaced vertically apart, may be provided, the key being provided with a like number of clearance-notches, each similar to 26', for coöperation, respectively, with such lugs.

To facilitate the shifting of the tumbler 90 as above explained, the body of such tumbler is provided with a suitable upright opening or recess 26'', into which enters the lateral lug of the key when the same is duly turned. Further, opening 26'' is preferably 95 flanked at its opposite sides by like openings which, in coöperation with the lateral lug of the key aforesigned, serve to permit such a readjustment of the tumbler as shall cause the pin 15' to ride into and occupy one 100 or the other of the pockets flanking the stop 11', should such pin at any time become casually centered on the apex of the stop.

To insure a more serviceable conjunction of the pin 15' with the tumbler made use of, 105 the same is fitted with a collet 27, at the inner face of the body of the tumbler, and with a disk-bushing 27' at the outer face thereof, said bushing working in the opening 15, the pin aforesigned being fitted with 110 the finger-button 16' outwardly beyond said bushing, and through the medium of which finger-button the tumbler may be actuated by finger-pressure independently of any key when desired and when the frame-sections 115 of the hand-bag or the like to which the lock may be applied, are unlocked, as will be readily understood.

In the operation of assembling the lock-mechanism availed of within the housing 120 provided therefor, springs 13, 18'' are contracted under finger-pressure applied oppositely to the thrust-plate 10 and, say, the follower thereabove; whereby the free ends of the guide-spindles 7, 7'' are caused to project somewhat above the top member of such follower, the free ends of said spindles being then projected freely upward through the top-plate 5' of the housing by way of 125 the openings provided therefor in such top- 130

plate and with the finger-piece 19" lying within the cut-away portion 20 of said top-plate. Whereupon the assembled lock-mechanism, with its springs aforesaid still 5 under contraction as stated, is carried forwardly into the housing and into its upright position therein. Whereupon the thrust-plate 10" is permitted to snap, under the stress of the controlling-springs aforesaid, 10 into its position of service within the housing, and wherein it detachedly overlies as stated the base 5 and is barred against casual displacement rearwardly with respect to such housing by means of the retaining-lip 15 6" afforded thereby. To remove the mechanism from the housing it is only needful to lift the thrust-plate 10", against the tendency of the springs aforesaid and sufficiently to clear the top of the retaining-lip 20 6", free withdrawal of the mechanism rearwardly from the housing being thereby permitted.

The operation of our improved lock should be apparent from the foregoing description thereof; and it will be further apparent that modifications thereof may be effected therein, when coming within the scope of the appended claims.

Having thus described our invention, we 30 claim:

1. A lock of the class herein described comprising suitable lock-mechanism and a housing therefor, said lock-mechanism including a spring-controlled locking-bolt, a follower detachedly bearing thereon and depressible in unison therewith; and a finger-piece, the latter rising fixedly from said follower and depressible therewith.
2. A lock of the class herein described 40 comprising suitable lock-mechanism and a housing therefor, said housing affording a retaining-lip whereby at the rear edge of its base-plate casual displacement of the mechanism from the interior of the housing is obviated, and being attachable to a frame-section of a hand-bag.

3. A lock of the class herein described comprising suitable lock-mechanism and a housing therefor, said lock-mechanism including a depressible bolt; and a hollow finger-piece whereby the bolt may be depressed by finger-pressure, said finger-piece having a major opening at its top; a key-way finder working partially in said opening; and a medium fixed within said finger-piece and whereby the key-way finder is held against casual displacement.

4. A lock of the class herein described comprising suitable lock-mechanism and a 60 housing therefor, said mechanism including a locking-bolt engageable with the tenon of a hasp; a thrust plate within and detachably overlying the base-plate of the housing; opposite guide-spindles rising fixedly and di-

rectly from the thrust-plate and freely piercing the locking-bolt thereabove; spiral springs interposed between said thrust-plate and said locking-bolt and exerting an elastic stress thereon; and means whereby the bolt may be depressed against the stress of said springs.

5. A lock of the class herein described comprising suitable lock-mechanism and a housing therefor, said lock-mechanism including a spring-pressed yoke crimped medially to form a depending stop, and further including a laterally shiftable tumbler, said tumbler fitted with a pin coöperating with said stop, and said pin being provided at its outer end, exteriorly of the front wall of the housing, with a finger-button, whereby, under finger-pressure duly applied thereto, the tumbler may be shifted laterally within the housing.

6. A lock of the class herein described comprising suitable lock mechanism and a housing therefor, said lock-mechanism including a locking-bolt; a follower thereon and depressible therewith; a tumbler shiftable laterally within the housing and fitted with a shoulder; a suitable spring controlling said locking bolt and tumbler jointly; and means whereby said tumbler may be laterally shifted to bring its shoulder aforesaid under a margin of said follower for locking the latter against depression.

7. For a lock mechanism of the class herein described, a locking-bolt follower consisting of a top-plate fitted with an irregular key-aperture, suitable downturned end-walls 100 and a downturned rear wall, the latter merged at its lower edge into a terminal flap returned beneath and into parallelism with the top-plate and fitted with a circular aperture at a point in vertical registry with 105 the irregular key-aperture thereabove.

8. For a lock-mechanism of the class herein described, a yoke consisting of a medial member crimped to form a depending V-shaped stop, flanked by pin-receiving pockets at its opposite sides, said yoke further comprising downturned end-members merged into opposite depressed feet.

9. For a lock of the class herein described, a hollow finger-piece having a sleeve fixed 115 therein and having a rotative key-way finder at the top of said sleeve, and held in place by, said finder suitably exposed at the top of said finger-piece.

10. For a lock-mechanism of the class herein described, a tumbler comprising a relatively thin upright body fitted with opposite shoulders, with a series of upright openings at its upper portion, and with an uninterrupted flat flange at its lower portion, said flange lying at an angle to said body.

11. A lock of the class herein described

- comprising suitable lock-mechanism and a housing therefor, said mechanism including a locking bolt having catches struck upwardly therefrom short of the ends thereof and so rendered engageable with the tenons of a hasp; means for exerting an elastic stress upwardly on said bolt; and means whereby the same may be depressed against such elastic stress.
- 10 12. A lock of the class herein described comprising suitable lock mechanism and a housing therefor, said mechanism including a locking bolt having upturned end-terminals and further having catches struck upwardly therefrom and so rendered engageable with the tenons of a hasp; means for exerting an elastic stress upwardly on said
- 5 bolt; and means whereby the same may be depressed against such elastic stress.
13. For a lock of the class herein described, a bolt having upstanding terminals at its extreme opposite ends and catches struck upwardly therefrom short of said terminals.
14. For a lock of the class herein described, a hollow finger-piece having a sleeve fixed therein, said sleeve fitted with an interior key-baffling lug, and having a rotative key-way finder at the top of and held in place by said sleeve, said finder suitably exposed at the top of said finger-piece.

BRODIE J. RICHARDSON.
CLAIRES BARBER.
